UNITED STATES PATENT OFFICE.

HERBERT M. DAWLEY, OF BUFFALO, NEW YORK, ASSIGNOR TO THE ADAMS & WESTLAKE COMPANY, A CORPORATION OF ILLINOIS.

DESIGN FOR A BODY FOR AUTOMOBILE-HEADLIGHTS.

42,794.

Specification for Design.

Patented July 16, 1912.

Application filed March 25, 1912. Serial No. 686,194. Term of patent 14 years.

To all whom it may concern:

Be it known that I, HERBERT M. DAWLEY, residing at Buffalo, county of Erie, and State of New York, have invented a new, original, and ornamental Design for Bodies for Automobile-Headlights, of which the following is a specification, reference being had to the accompanying drawings, forming a part hereof and showing a side view of the headlight-body.

The distinctive characteristic of the design is that the body is bell-shaped.

I claim—

The ornamental design for a body for automobile headlights, as shown and described.

HERBERT M. DAWLEY.
